UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,309,416.

Specification of Letters Patent.

Patented July 8, 1919.

Application filed November 3, 1917. Serial No. 200,031.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States to O. Mergenthaler No. 436,532, wherein circulating matrices are released from a magazine in the order in which their characters are to appear in print, and then assembled in line, the composed line transferred to the face of a mold, the mold filled with molten metal 15 to form a slug or linotype against the matrices which produce the type characters thereon, and the matrices thereafter elevated and returned through distributing mechanism to the magazine from which they 20 started.

More particularly, it relates to machines 25 of the kind now in commercial use, wherein, in addition to the main magazine or magazines, a supplemental magazine is also employed, the latter being arranged in a vertical location different from that of the main magazines and at the side thereof, or to employ the term recognized in the art, in "tandem" thereto. All these magazines are 30 equipped with escapements, and it is among the purposes of my invention to provide actuating devices therefor which will be operable from a common keyboard, so that by its manipulation the operator may release matrices 35 from any selected magazine at will.

In the accompanying drawings, I have 40 illustrated my improvements merely in preferred form and by way of example, and as applied to the particular style of machine 45 mentioned, but obviously many changes and variations may be made therein, and in their mode of application, which will still be comprised within the spirit of my invention. Further, my improvements are readily 50 adaptable to other forms of typographical machines, such as those that handle type or dies, instead of matrices. Generally speaking, I desire it to be understood that I do

not limit myself to any specific form or embodiment, except in so far as such limitations are specified in the claims.

Referring to the drawings:

Figure 1 is a front elevation of a portion of the machine with my improvements applied thereto;

Fig. 2 is an enlarged skeleton perspective of the parts embodying the invention; and

Fig. 3 is an elevation of certain of these parts, showing them in different positions.

As seen in Fig. 1, the machine is equipped with two superposed main magazines A and A¹ and a single supplemental magazine B arranged in tandem thereto. It will be understood that any convenient number of both main and tandem magazines may be employed, and that the showing in the drawings is merely illustrative of the general principle involved.

The magazines A and A¹ are equipped with the customary escapements C, each comprising a pivoted lever and two connected pawls which are alternately projected into the magazine channel to engage with the matrices X therein, the escapement being under the control of a spring C¹, which tends to withdraw the lowermost pawl and project the upper one. As shown in Fig. 2, the escapements C are reversely actuated by the pivoted levers E in engagement therewith, the levers E in turn being operated by the vertical slides E¹ formed with projections E² to engage over the outer ends of the levers. Each of the slides E¹ is provided with a spring E³, of greater strength than that of the spring C¹, so that normally the slide is drawn downward and the lower pawl of the escapement projected into the magazine channel to hold the leading matrix therein. When the slide E¹ is moved upwardly, the spring C¹ is permitted to act in the well-known manner to release this matrix, all in the manner well understood in the art. The slides E¹ are elevated by the levers E⁴, which are operated by the reeds E⁵, cam yokes E⁶, cams E⁸ and actuating roller E⁹, the cam yokes being under the control of the triggers E¹⁰, slides E¹¹ and the keys F of the keyboard.

The main magazines are each provided with matrix locking means, such as the rock

shaft G, which in one position engages the escapements C so as to move them against the force of the springs C¹ and thereby hold all the matrices in the magazine (see Fig. 5 2), and in the other position releases the escapements so that they may be actuated, in the manner already described, from the keys F. The operating means for the locking rock shaft comprise the link G¹ and 10 the spring G³ connected to the arm or projection G¹⁰ on the link, the spring being so arranged that normally the rock shaft is in its active or locking position. To move the link G¹ in the opposite direction against 15 the force of the spring G³, so as to release the escapements, the link is connected at its lower end to a pivoted lever G², which in turn is moved by the slide G⁴, cam yoke G⁵, cam G⁶ and actuating roller G⁷, the cam 20 yoke G⁵ being normally supported by a trigger G⁸, which is connected by the bent member G⁹ to a key J or H preferably mounted in convenient proximity to the main keyboard, as best shown in Fig. 1.

25 The locking devices of the two superposed magazines are substantially the same, they being respectively controlled by the two keys, J and H, the actuation of the key J effecting the unlocking of the matrices in 30 the upper magazine, and the actuation of the key H effecting the unlocking of the matrices in the lower magazine. When one of these keys is operated and the link G¹ depressed, the corresponding locking devices 35 are held in inactive position by the detent bar K formed with hooks or dents K² located in position to engage the operated lever G² (see Fig. 3). The spring K¹ normally holds the bar K toward the right, 40 but permits it to be moved toward the left when the beveled upper portion of the hook K² is encountered by the lever G², after which the spring restores the bar to its first position and the locking devices remain inactive 45 until they are released in the manner subsequently to be pointed out.

The parts so far described and their mode of operation are not substantially different from those illustrated in my Letters Patent 50 No. 1,288,913, dated December 24, 1918, to which reference may be had, if desired, for a fuller understanding of the mechanism.

Turning now to the supplemental or tandem magazine B, it is provided with similar 55 escapements D, which are operated in one direction by springs D¹ and in the other by reeds O, which are constantly urged downward as usual by stronger springs (not shown). It is part of my invention 60 to provide mechanism whereby the reeds O are actuated from the regular keys F, which control the escapements of the main magazine through the direct connections already noted, and this I effect by the 65 provision of indirect connections next to be

described, so that a single key F is capable of releasing matrices at will from the corresponding channel of either one of the main magazines or from the corresponding channel of the tandem magazine. In this 70 way, I materially simplify the operation of the machine and am enabled to dispense with the second keyboard ordinarily employed in the commercial machine in connection with the tandem magazine. 75

To effect the connection of the escapement actuating means of the main magazines to the reeds of the tandem magazine, I employ indirect connections from the main reeds E⁵ to the corresponding supplemental reeds 80 O, certain or all of the reeds E⁵ being formed with projections M which engage under the outer ends of levers M¹ pivoted at M² to the framework, the other ends of the levers being jointed to the ends of 85 pivoted levers N¹, the farther ends of which engage under projections N upon the supplemental reeds O, all in such manner that when the parts are in operative relation, as shown in Fig. 2, the elevation of a reed 90 E⁵ effects the elevation of the corresponding reed O and permits the spring D¹ to operate the escapement D. When the reed E⁵ again descends, the reed O also descends and the escapement D returns to its original 95 position. Preferably and as shown, the connecting levers M¹ and N¹ are disposed in groups each comprising a plurality of such levers which are mounted upon common pivots; and the projections M and N on the 100 reeds E⁵ and O respectively are arranged in similar groups to correspond, the projections in each group being of different extents so as to engage the appropriate levers only of the corresponding group, as clearly 105 indicated in Fig. 2.

It will be noted (see Fig. 3) that the levers N¹ are pivoted at N² to the movable member or fulcrum slide P, which is normally urged downward by the connected 110 spring P¹. The parts are so arranged and proportioned that at this time, and due to the lowering of the fulcrum of the levers N¹, the outer ends of the levers M¹ will be so elevated above the projections M, and the outer ends of the levers N¹ will be so depressed below the projections N, that the elevation of a reed E⁵ is not attended by the elevation of the corresponding reed O, and consequently matrices will not be released 115 from the magazine B. However, when the fulcrum slide P is in its elevated position (see Fig. 2), the parts will operate in the manner previously described. 120

I preferably control the position of the 125 fulcrum slide P by automatic connections to the matrix locking devices of the main magazines. At the lower end of the slide P is mounted a transverse member P², centrally pivoted thereto at P³, so that it projects in 130

opposite directions therefrom in position to engage at opposite sides with the bent arms or projections G^{10} upon the locking links G^1 . The parts are so arranged that when the locking devices are in their normal or active position (see Fig. 2), the two arms G^{10} will both act upon the member P^2 and support the slide P in its uppermost or active position, at which time matrices may be freely drawn from the magazine B by the actuation of the common keys F. In other words, when the tandem magazine is in condition to deliver matrices, the matrices in the main magazines are locked.

If it be desired to deliver matrices from one of the main magazines, the corresponding key J or H is actuated, resulting in the depression of the link G^1 to unlock the matrices in the magazine, which depression of the link (see Fig. 3) removes the bent arm G^{10} from under the end of the member P^2 , and the slide P is depressed, thereby breaking the indirect connection of the reeds O and the reeds E⁵. At this time the operation of the character keys F results in the actuation of the escapements of the main magazine which has been unlocked, and of that magazine alone.

As previously noted, and as shown in Fig. 3, when the key J or H has been actuated, the locking devices are held in inactive position by the engagement of a hook K² with the lever G², and this relation continues until the parts are released by the next operation of the bar K. For instance, if it next be desired to deliver matrices from the other main magazine, the other key H or J is operated and the former operation is substantially duplicated, it being merely pointed out that the longitudinal movement of the locking bar K by the new lever G² effects the release of the previously held lever G², so that its connected locking devices may return to active position. Now, matrices may be released from the second main magazine and from that one only.

If now it be desired to release matrices from the tandem magazine B, because of the construction and operation previously explained, it is necessary merely to release the lever G² from the locking bar K, which results in leaving all the main magazines with their matrices locked therein, and the consequent restoration of the fulcrum slide P to its active position, so as to restore the connection between the reeds O and reeds E⁵. This releasing movement of the bar K may be conveniently effected by a key L formed at one end with an offset projection L¹ adapted to engage a pin K⁴ upon the end of the bar, in such manner that when the key is operated, the bar is moved, releasing the lever G² that is held thereby, with the result of locking the matrices in the main magazines and effecting the connection of the es-

capement actuating devices of the tandem magazine with the common keys of the keyboard mechanism.

It will be noted that there is a key for each of the magazines, key H for the lower main magazine, key J for the upper main magazine, and key L for the auxiliary tandem magazine, and that the operation of any one of them renders the corresponding magazine active because of the connections already outlined. This arrangement affords a simple and convenient means for the operator to bring any desired font into use merely by touching the appropriate key; and he is then enabled to deliver matrices from the selected magazine by the actuation of the common character keys, quite irrespective of whether the matrices be located in the main magazines or in a tandem magazine.

In my preferred form I have shown the escapement actuating devices for the tandem magazine as automatically controlled by the matrix locking devices of the other magazines, as this is a convenient and simple way of securing the desired result, but I do not limit myself to the particular construction and arrangement thus involved. Neither do I limit myself to the specific form of connections for actuating the escapements of the tandem magazine. Again, although in my preferred form I have shown special keys for rendering the several magazines active, which keys are or may be actuated from time to time, I do not limit myself to the use of such special keys for this purpose, as the automatic controlling devices might if desired be actuated from other periodically operated parts. These constructions may be materially varied; and many other modifications and alterations in my improvements and in their mode of application will suggest themselves to those skilled in the art without departure from the scope of the invention.

Having thus described my invention, its construction and mode of operation, what I claim and desire to secure by Letters Patent of the United States, is as follows:

1. In a typographical machine, the combination of two matrix magazines arranged in tandem, escapements for each of the magazines and operating devices therefor, two selecting keys, one for each magazine, and connections from each of the keys to the operating devices whereby matrices may be released at will from either magazine upon the actuation of the corresponding key.

2. In a typographical machine, the combination of a plurality of superposed matrix magazines, a further matrix magazine arranged in tandem, escapements for each of the magazines and operating devices therefor, a plurality of selecting keys, one for each magazine, and connections from each of the keys to the operating devices whereby

matrices may be released at will from any one of the magazines upon the actuation of the corresponding key.

3. In a typographical machine, the combination of two matrix magazines arranged in tandem, escapements for each of the magazines, common keyboard devices connected directly to the escapements of one of the magazines and indirectly by supplemental means from the direct connections to those of the other, and controlling devices whereby matrices may be released at will from either magazine.

4. In a typographical machine, the combination of a plurality of superposed matrix magazines, a further matrix magazine arranged in tandem, escapements for each of the magazines, common keyboard devices connected directly to the escapements of the superposed magazines and indirectly by supplemental means from the direct connections to those of the tandem magazine, and controlling devices whereby matrices may be released at will from any one of the magazines.

5. In a typographical machine, the combination of two matrix magazines arranged in tandem, escapements for each of the magazines, common keyboard devices connected directly to the escapements of one of the magazines and indirectly to those of the other, two selecting keys, one for each magazine, and connections from each of the keys to the keyboard devices whereby matrices may be released at will from either magazine upon the actuation of the corresponding key.

6. In a typographical machine, the combination of a plurality of superposed matrix magazines, a further matrix magazine arranged in tandem, escapements for each of the magazines, common keyboard devices connected directly to the escapements of the superposed magazines and indirectly to those of the tandem magazine, a plurality of selecting keys, one for each magazine, and connections from each of the keys to the keyboard devices whereby matrices may be released at will from any one of the magazines upon the actuation of the corresponding key.

7. In a typographical machine, the combination of two matrix magazines arranged in tandem, escapements for each of said magazines and operating devices therefor, keyboard mechanism comprising a single key for corresponding escapements of both magazines, locking devices for the matrices of one of the magazines, and connections whereby the locking of the matrices therein permits the actuation by said key of the corresponding escapement of the other magazine.

8. In a typographical machine, the combination of a plurality of superposed matrix

magazines, a further matrix magazine arranged in tandem, escapements for each of said magazines and operating devices therefor, keyboard mechanism comprising a single key for corresponding escapements of all of said magazines, locking devices for the matrices of the superposed magazines, and connections whereby the locking of the matrices therein permits the actuation by said key of the corresponding escapement of the tandem magazine.

9. In a typographical machine, the combination of two matrix magazines arranged in tandem, escapements for each of said magazines and operating devices therefor, normally active matrix locking devices for one of the magazines, a key for moving the locking devices to inactive position to permit the release of matrices from said magazine, and a further key and connections to return the locking devices to active position and to permit the release of matrices from the other magazine.

10. In a typographical machine, the combination of a plurality of superposed matrix magazines, a further matrix magazine arranged in tandem, escapements for each of said magazines and operating devices therefor, normally active matrix locking devices for each of the superposed magazines, a plurality of keys, one for each of the superposed magazines, and respective connections to move the locking devices to inactive position to permit the release of matrices from the corresponding magazine, and a further key and connections to restore the locking devices to active position and to permit the release of matrices from the tandem magazine.

11. In a typographical machine, the combination of two matrix magazines arranged in tandem, escapements for each of said magazines, common keyboard mechanism connected directly to the escapements of one magazine and indirectly to those of the other, said keyboard mechanism comprising a single key for corresponding escapements of the two magazines, matrix-locking devices for one of said magazines, and connections whereby the locking of the matrices therein permits the actuation by said key of the corresponding escapement of the other magazine.

12. In a typographical machine, the combination of a plurality of superposed matrix magazines, a further matrix magazine arranged in tandem, escapements for each of said magazines, common keyboard mechanism connected directly to the escapements of the superposed magazines and indirectly to those of the tandem magazine, said keyboard mechanism comprising a single key for corresponding escapements of all of said magazines, matrix locking devices for each of the superposed magazines, and connec-

tions whereby the locking of matrices in the superposed magazines permits the actuation by said key of the corresponding escapement of the tandem magazine.

5 13. In a typographical machine, the combination of two matrix magazines arranged in tandem, escapements for both of said magazines, keyboard mechanism, locking devices for the matrices in one of the magazines, and connections therefrom to control the operative connection and disconnection to the keyboard mechanism of the escapements of the other magazine.

10 14. In a typographical machine, the combination of a plurality of superposed matrix magazines, a further matrix magazine arranged in tandem, escapements for all of said magazines, keyboard mechanism, locking devices for the matrices of the superposed magazines, and connections therefrom to control the operative connection and disconnection to the keyboard mechanism of the escapements of the tandem magazine.

15 15. In a typographical machine, the combination of two matrix magazines arranged in tandem, escapements for each of said magazines, a single keyboard mechanism for both sets of escapements, normally active matrix locking devices for one of said magazines, a key to move said locking devices to inactive position, a further key to restore them to active position, and connections whereby the disengagement or engagement of the keyboard mechanism with the escapements of the second magazine is controlled by the respective actuation of said keys.

20 16. In a typographical machine, the combination of a plurality of superposed matrix magazines, a further matrix magazine arranged in tandem, escapements for each of said magazines, a single keyboard mechanism for the escapements of all of said magazines, normally active matrix locking devices for each of the superposed magazines, a key for each of said superposed magazines to move its locking devices to inactive position, a further key to restore said locking devices to active position, and connections whereby the disengagement or 25 engagement of the keyboard mechanism with the escapements of the tandem magazine is controlled by the respective actuation of said keys.

30 17. In a typographical machine, the combination of two matrix magazines arranged in tandem, escapements for each of said magazines, and a single keyboard mechanism connected directly to the escapements of one magazine and indirectly to those of the other, the connecting parts comprising an adjustable member which in one position permits the actuation of the escapements of the second magazine and in the other position prevents it.

35 18. In a typographical machine, the com-

bination of a plurality of superposed magazines, a further matrix magazine arranged in tandem, escapements for each of said magazines, and a single keyboard mechanism connected directly to the escapements 70 of the superposed magazines and indirectly to those of the tandem magazine, the connecting parts comprising an adjustable member which in one position permits the actuation of the escapements of the tandem 75 magazine and in the other position prevents it.

19. In a typographical machine, the combination of two matrix magazines arranged in tandem, escapements for each of said 80 magazines, a single keyboard mechanism connected directly to the escapements of one magazine and indirectly to those of the other, the connecting parts comprising an adjustable member which in one position 85 permits the actuation of the escapements of one of the magazines and in the other position prevents it, locking devices for the matrices of the other magazine, and connections whereby the position of said adjustable member is controlled by that of the locking devices.

20. In a typographical machine, the combination of a plurality of superposed matrix magazines, a further matrix magazine arranged in tandem, escapements for all of said magazines, a single keyboard mechanism connected directly to the escapements of the superposed magazines and indirectly to those of the tandem magazine, the connecting parts comprising an adjustable member which in one position permits the actuation of the escapements of the tandem magazine and in the other position prevents it, locking devices for the matrices of the superposed magazines, and connections whereby the position of said adjustable member is controlled by that of the locking devices.

21. In a typographical machine, the combination of two matrix magazines arranged in tandem, escapements for each of said magazines, and a single keyboard mechanism connected directly to the escapements of one magazine and indirectly to those of the other, the connecting parts comprising a pivoted lever and an adjustable fulcrum therefor, which in one position permits the actuation of the corresponding escapement of the second magazine and in the other prevents it.

22. In a typographical machine, the combination of a plurality of superposed matrix magazines, a further magazine arranged in tandem, escapements for all of said magazines, and a single keyboard mechanism connected directly to the escapements of the superposed magazines and indirectly to those of the tandem magazine, the connecting parts comprising a pivoted lever and an 125

adjustable fulcrum therefor, which in one position permits the actuation of the corresponding escapement of the tandem magazine and in the other position prevents it.

23. In a typographical machine, the combination of two matrix magazines arranged in tandem, escapements for each of said magazines, a single keyboard mechanism connected directly to the escapements of one magazine and indirectly to those of the other, the connecting parts comprising a pivoted lever and an adjustable fulcrum therefor, which in one position permits the actuation of the corresponding escapement of the second magazine and in the other position prevents it, locking devices for the matrices of the first magazine, and connections whereby the position of the adjustable fulcrum is controlled by that of the locking devices.

24. In a typographical machine, the combination of a plurality of superposed matrix magazines, a further matrix magazine arranged in tandem, escapements for all of said magazines, a single keyboard mechanism connected directly to the escapements of the superposed magazines and indirectly to those of the tandem magazine, the connecting parts comprising a pivoted lever and an adjustable fulcrum therefor, which in one position permits the actuation of the corresponding escapement of the tandem magazine and in the other position prevents it, locking devices for the matrices of the superposed magazines, and connections whereby the position of the adjustable fulcrum is controlled by that of the locking devices.

25. In a typographical machine, the combination of two matrix magazines arranged in tandem, escapements for each of said magazines and operating devices therefor, keyboard mechanism comprising a single key for the corresponding escapements of both magazines, and controlling devices actuatable to cause said key to deliver matrices from the magazines alternately.

26. In a typographical machine, the combination of a plurality of superposed matrix magazines, a further matrix magazine arranged in tandem, escapements for each of said magazines and operating devices therefor, keyboard mechanism comprising a single key for corresponding escapements of all said magazines, and controlling devices actuatable to cause said key to deliver matrices from the several magazines in the required manner.

27. In a typographical machine, the combination of two magazines arranged in tandem and each having escapements to control the release of matrices therefrom, a set of key controlled actuating devices for the escapements of one magazine, a second set of actuating devices for the escapements of the

other magazine, connections between the corresponding actuating devices of the two sets, and means operable to permit the release of matrices from one magazine and to prevent their release from the other, and vice versa, whereby either magazine may be rendered active and the other inactive as required.

28. A combination as specified in claim 27, characterized by the fact that the means which permit and prevent the release of matrices from one magazine include a matrix locking device movable to active and inactive position as the other magazine is rendered active and inactive respectively.

29. A combination as specified in claim 27, characterized by the fact that the means which permit and prevent the release of matrices from one magazine include a member for breaking and making the connections between the two sets of actuating devices as the other magazine is rendered active and inactive respectively.

30. A combination as specified in claim 27, embodying two magazine selecting keys controlling the operation of the means therein recited in such manner that the actuation of either key renders its corresponding magazine active and the other magazine inactive.

31. A combination as specified in claim 27, embodying a further magazine having escapements operated by one of the sets of actuating devices and characterized by the fact that the means therein recited are also operable to permit and prevent the release of matrices from said further magazine according as the other magazines are rendered active or inactive.

32. A combination as specified in claim 31, characterized by the fact that the escapements of the further magazine therein recited are operated by the first set of actuating devices as distinguished from the second set.

33. A structure as specified in claim 31 embodying a third magazine selecting key for the further magazine therein recited, characterized by the fact that said key, in conjunction with the other two selecting keys, acts to control the operation of the means mentioned in such manner that the actuation of any given key renders the corresponding magazine active and the remaining magazines inactive.

34. In a typographical machine, the combination of two magazines arranged in tandem and each having escapements to control the release of matrices therefrom, a set of key controlled actuating devices for the escapements of one magazine, a second set of actuating devices for the escapements of the other magazine, and means whereby the corresponding actuating devices of the two sets may be connected and disconnected as required.

35. In a typographical machine, the com-

bination with a main magazine and an auxiliary magazine, the two magazines being arranged in tandem and each having escapements to control the release of matrices therefrom, of a keyboard common to both magazines, and means whereby the escapements of the auxiliary magazine are controlled from the keyboard, the said means including a set of actuating devices arranged 10 in operative relation to the escapements of

said auxiliary magazine, a corresponding set of actuating devices controlled directly from the keyboard, and intermediate members connecting the two sets of actuating devices and transmitting motion from the first to 15 the second mentioned set.

In testimony whereof, I have affixed my signature hereto.

DAVID S. KENNEDY.
